UNITED STATES PATENT OFFICE.

FRED BECK, OF CHATSWORTH, IOWA.

HOISTING MECHANISM.

1,247,067.

Specification of Letters Patent. Patented Nov. 20, 1917.

Application filed February 5, 1917. Serial No. 146,593.

To all whom it may concern:

Be it known that I, FRED BECK, a citizen of the United States, and a resident of Chatsworth, in the county of Sioux and 5 State of Iowa, have invented certain new and useful Improvements in Hoisting Mechanism, of which the following is a specification.

The present invention relates to hoisting 10 mechanism and more particularly to mechanism of this class employed for operating hay-hoists.

The invention has for its primary object 15 the production of an improved hoisting mechanism inexpensive and simple in construction, thoroughly efficient in operation and requiring but a minimum of power.

Another object of the invention is the 20 production of improved mechanism for controlling the hoisting and trip ropes of hay-hoists.

A further object of the invention is the 25 production of an improved clutch-mechanism for the control of alternately operated reels.

With these and other objects in view, the invention, consisting in the construction, combination and novel arrangement of parts 30 will be fully understood from the following description, reference being had to the accompanying drawings, which form a part of this application and in which like characters of reference indicate corresponding parts throughout the several views, of which,

35 Figure 1 is a side elevation of a hay-hoisting mechanism constructed in accordance with the invention;

Fig. 2 is an enlarged plan of the power mechanism;

40 Fig. 3 is a front elevation of the same, the sweep being omitted;

Fig. 4 is a side elevation of the same;

Fig. 5 is a longitudinal section of the 45 clutch mechanism and members associated therewith; and

Fig. 6 is a side elevation of one of the reels.

Referring, now, to the illustrations the 50 hay-hoisting mechanism consists of a hay-grapple, 7, depending by a hoisting rope, 8, from a truck, 9, mounted to travel to and fro on a supporting rail, 10. The grapple is provided with a trip, 11, which when actuated permits the grapple to release the 55 hay. The trip is connected with a trip rope, 12. The hoisting rope passes over direc-

tion pulleys, 13, and operates to elevate the hay-grapple and draw the truck along the supporting rail.

The above described mechanism represents no part of the present invention, but serves to illustrate the general and familiar hay hoisting mechanism for which my invention is particularly adapted. The hoisting and trip ropes are wound upon power- 60 actuated reels and means are provided for alternately actuating the reels to control the ropes.

In the present embodiment the power-hoisting mechanism consists of a suitable 70 base, 14, on which are mounted uprights, 15, having mounted at their upper ends, friction rollers, 16, which rotatably support a flanged crown wheel, 17, intermeshed with a spur gear, 18, rotatably supported by one 75 of the uprights and intermeshed with a relatively larger spur gear, 19, fixed on a horizontal shaft, 20, journaled in suitable bearings, 21, on opposite uprights. Upon the shaft are freely mounted reels 22, and 23, 80 the reels being provided with brake drums, 24, around which pass brake bands 25, controlled by levers, 26, fulcrumed on suitable bearings, 27, on the base.

On the shaft, 20, adjacent the reels are 85 fixed blocks, 28, provided with diametrically opposite openings, 29, through which freely pass rods, 30, carried by an intermediate collar, 31, freely mounted on the shaft, 20, and provided with an annular groove, 90 32 within which is engaged a ring, 33, formed on a lever, 34, fulcrumed at its lower end on a suitable bearing, 35, mounted on the base. Interposed between the blocks, 28, and the collar, 31 and mounted upon the 95 rods, 30, are compression-springs, 36, which serve to normally maintain the collar, 31, in the center between the blocks, 28.

The faces of the reels are provided with 100 pockets, 37, positioned to receive the ends of the rods, 30. Upon the reels 22 and 23 are secured the hoisting and trip ropes respectively. On the crown wheel, 17, is secured a radial sweep arm, 38, to which may be hitched draft animals to actuate the device; 105 or if desired the device may be actuated by a driven belt applied to the pulley, 39, mounted on the shaft, 20.

By virtue of the construction now set 110 forth, it is evident that the lever, 34, may be moved in opposite directions to alternately actuate the reels. Thus to impart

traction on the hoisting rope, 8, it is only necessary to move the lever, 34 in the direction of the reels, 22, then when the grapple has been elevated and drawn to the point desired, the lever is thrown in the opposite direction thereby releasing the reel, 22, and actuating the companion reel to release the trip and retract the truck and grapple. Through the medium of the brake levers, 10 26, the reels are prevented from spinning too rapidly when released.

Having thus described my invention, what I claim as new and desire to secure by Letters Patent of the United States, is,—
15 1. In a hoisting mechanism, a rotatable shaft, a pair of reels freely mounted thereon, blocks fixed on the shaft adjacent the reels, a collar encircling the shaft between the blocks, rods carried by the collar and 20 slidable through the blocks, compression-

springs interposed between the collar and the blocks, the faces of the reels being recessed to receive the ends of the rods, and the collar being movable in opposite directions longitudinally of the shaft to cause 25 the reels to be alternately engaged by the rods.

2. In a hoisting mechanism, a base, uprights mounted thereon, friction-rollers on the uprights, a crown wheel rotatably supported by the rollers, a horizontal shaft rotatably supported by the uprights, a gear on the shaft driven by the crown-wheel, a pair of reels freely mounted on the shaft, and clutch mechanism between the reels operable to alternately actuate the reels. 30 35

In testimony whereof, I have hereunto set my hand this 18 day of January, 1917.

FRED BECK.
